UNITED STATES PATENT OFFICE.

JAMES R. CARDWELL, OF CHICAGO, ILLINOIS, ASSIGNOR TO UNION DRAFT GEAR COMPANY, OF CHICAGO, ILLINOIS, A CORPORATION OF DELAWARE.

DRAFT GEAR.

Application filed December 14, 1923. Serial No. 680,589.

The invention relates to draft gears for railway cars, of the friction type, its objects being to secure a high degree of efficiency, smoothness of action and certainty and 5 smoothness of release.

The invention consists of a structure comprising groups of intercalating friction plates, toggle elements for pressing the plates together, and means by which the 10 toggle elements are actuated. It consists further in various features of improvement as will appear in connection with the description of the device.

In the drawings illustrating a preferred 15 form of construction,

Fig. 1 is a central plan section of the gear, associated elements of the car frame being shown in detail;

Fig. 2 is a sectional view of the gear on 20 the line 2—2 of Fig. 1;

Fig. 3 is a view similar to Fig. 1, the gear being under compression, some of the parts being shown in plan and some broken away;

Fig. 4 is a view in perspective of one of 25 the friction shoes of the gear;

Fig. 5 is an end elevation of a combined friction spring seat and actuating bar; and

Fig. 6 is a view in perspective of one of the friction plates.

The gear is adapted for use in connection with the standard form of railway car and 30 coupler, and in service is mounted between two draft sills 10 and cooperates with a pair of draft lugs 11, 12 and a pair of buffing lugs 13, 14, attached to the sills, and is actuated by a coupler 15 having any desired 35 form of loop or extension as indicated at 16.

The improved gear comprises a pair of 40 chambered followers 17, 18, which engage respectively the draft and buffing lugs. Within these followers is mounted two 45 groups of intercalating friction plates 19, 20. The friction plates, one of which is shown in perspective in Fig. 6 and designated by the numeral 21, are alike in shape, having, generally speaking, an oblong, rectangular form. Each is provided near one 50 end with lateral recesses 22, 23, forming shoulders for engagement by an actuating bar, and at the opposite end having its side 55 margins cut away as indicated at 24, 25, to provide clearance for the actuating bar associated with the companion set of plates.

Each group of plates is made up of two sets reversely arranged, one set as 26 having 55 its recessed ends located adjacent the end wall of the follower 17 and the other set 27 located adjacent the end wall of the follower 18. The length of the plates is slightly less than the distance between the 60 end walls of the two followers when the gear is fully compressed.

Housed within each of the followers is a pair of friction shoes 28, 29 and 30, 31, the members of each pair being on opposite 65 sides of the axis of the gear and slidably engaging the inner plate of the adjacent group. These friction shoes are alike in form, one of them being shown in perspective in Fig. 4. Each is provided on its inner face with a vertical pivot rib 32. A pair of toggle elements 33, 34, and 35, 36 is interposed between the members of each pair of friction shoes and recessed to engage and turn upon the ribs 32. The adjacent 70 faces of each pair of toggle members are curved and lie in contact. At the inner end of the curved face of each there is formed a shoulder for engagement by an abutment bar 37, 38 carried by a spring seat 75 39, 40. Reacting between the two spring seats 39, 40 is a spring 41, or as shown a pair of nested springs, which, through the bars 37, 38, resist forward movement of the toggle elements as the gear is compressed. 80 The actuating bars, as 42, 43, are four in number, one pair being associated with corresponding sets of friction plates of each group and engaging in the recesses at the tops and bottoms thereof, the inner shoulders of the several plates being normally in engagement with the end portions of the bars 37, 38 as indicated in Fig. 1.

In advance of the pivot ribs 32 each of the friction shoes as 28 is provided with a 85 forwardly facing shoulder 44. An annular spring seat 45, 46 cooperates with the shoulders of each pair of friction shoes and between these seats there reacts a releasing spring 47.

The cross members of both followers are centrally apertured as shown at 48, 49 for the admission of a bolt, not shown, for holding the elements of the gear in assembled relation preliminary to installation, which bolt may, if desired, be removed when the 105

gear is placed in service. The spring seats 39, 40 are apertured as shown at 50 and the several toggle members are grooved as shown at 51, to provide clearance for such rod.

Normally the elements of the gear as described occupy the positions as shown in Fig. 1, the side walls of the two followers being spaced apart a distance equal to the maximum compressive movement of the gear. Upon advance movement of either follower the friction shoes associated with it are carried forwardly against the resistance of the spring 47. The toggle elements associated with these shoes are urged forwardly against the abutment bar 37 or 38 and by reason of the resistance of the spring 41 both pairs of toggle elements are caused to turn on their pivots, their contacting faces rolling, each upon the other, the friction shoes being thus urged outwardly and pressing the friction plates together.

As the follower continues to advance the friction plates directly associated therewith are carried forward, sliding between the plates of the cooperating set. The actuating bars as 42 associated with the plates which are urged forward are carried with them, the abutment bars as 37, however, moving out of contact with the actuating bars as the travel of the latter does not commence until the ends of the friction plates as 26, which are normally spaced a short distance from the adjacent end wall of the follower, are engaged thereby.

The compressive action upon the friction plates due to the relative movement of cooperating toggle members gradually increases during the compression of the gear, due to the cumulative resistance of the spring 41.

Upon the relief of the stresses which have caused the compression of the gear, release is effected by the spring 47, which, being more powerful than the spring 41, forces back the friction shoes with greater force than is applied to the toggle elements by the latter spring. The compressive action upon the plates is thus relieved and the latter are restored to normal position by the bars as 42, which are carried backwardly by the bars as 37.

The shocks of service are absorbed by the springs and by the friction developed between the plates themselves and between the outer and inner plates, respectively, and the side walls of the followers and the friction shoes. The resistance to compression of the gear being gradually developed, the action is smooth and as the spring 41 tends at all times to spread the toggle elements the release is correspondingly smooth, though rendered certain by the preponderating power of the spring 47.

While a highly efficient, and so far as now advised, preferred form of construc-

tion is illustrated, various changes in the form and arrangement of the parts may be made within its scope.

I claim as my invention:

1. In a draft gear, in combination, a pair of chambered followers, two groups of intercalating friction plates housed within the followers, a pair of friction shoes housed within each follower and in engagement with the end wall thereof, the shoes of each pair bearing outwardly against the friction plates, a pair of toggle elements co-operating with each pair of shoes, a spring reacting between the two sets of toggle elements, a spring reacting between the two pairs of shoes, and means for retracting the advanced plates upon release. 70

2. In a draft gear, in combination, a pair of chambered followers, two groups of intercalating friction plates housed within the followers, a pair of friction shoes housed within each follower and in engagement with the end wall thereof, the shoes of each pair bearing outwardly against the friction plates, a pair of toggle elements co-operating with each pair of shoes, a spring reacting between the two sets of toggle elements, a spring of greater power reacting between the two pairs of shoes, and means for retracting the advanced plates upon release. 85

3. In a draft gear, in combination, a pair of chambered followers, two groups of intercalating friction plates housed within the followers, a pair of friction shoes housed within each follower and bearing laterally against the friction plates, each shoe being formed with a pivot rib, and a forwardly facing shoulder, a pair of toggle elements within each follower, each of such elements pivotally engaging one of the pivot ribs, a spring reacting between the two sets of toggle elements, a spring reacting between the shoulders of shoes at opposite ends of the gear and means for retracting the advanced plates upon release. 100

4. In a draft gear, in combination, a pair of chambered followers, two groups of intercalating friction plates housed within the followers, a pair of friction shoes housed within each follower and in engagement with the end wall thereof, the shoes of each pair bearing outwardly against the friction plates, a pair of toggle elements co-operating with each pair of shoes, a spring reacting between the two sets of toggle elements and a spring reacting between the two pairs of shoes, a retracting bar within each follower engaging shoulders on one set of friction plates of each group and being acted upon by the first named spring. 115

5. A draft gear including a pair of followers, means whereby one of said followers is moved toward the other when the gear is subjected to compressive strains, two sets of 120

intercalated friction plates, means whereby said plates are caused frictionally to resist movement of said followers, said last named means including a toggle mechanism operable when either follower is moved towards the other to force said plates into frictional engagement with one another, and means to release said plates from frictional engagement with one another when compression strains on the gear are removed.

6. A draft gear including a pair of followers, means whereby one of said followers is moved towards the other when the gear is subjected to compressive strains, two sets of intercalated friction plates, means whereby said plates are caused frictionally to resist movement of said followers, said last named means including a toggle mechanism between said plates and one of said followers operable when either follower is moved towards the other to force said plates into frictional engagement with one another, and means to release said plates from frictional engagement with one another when compression strains on the gear are released.

7. A draft gear including a pair of followers, means whereby one of said followers is moved towards the other when the gear is subjected to compressive strains, two sets of intercalating friction plates, means whereby said plates are caused frictionally to resist movement of said followers, said last named means including a toggle mechanism between said plates and one of said followers and an application spring between said toggle mechanism and the other of said followers through which movements of said followers are transmitted to said toggle mechanism to cause the latter to force said

plates into frictional engagement with one another, and means to release said plates from frictional engagement with one another when compressive strains on the gear are removed.

8. A draft gear including an inner follower, an outer follower, stop means limiting inward movement of the inner follower and outward movement of the outer follower, a yoke surrounding said followers, a coupler stem connected with said yoke for limiting longitudinal movement with respect thereto, the inner end of said coupler stem being in abutting relation to said outer follower, two sets of intercalated friction plates one set of which is arranged to be moved outwardly by said inner follower and the other set of which is arranged to be moved inwardly by said outer follower, a toggle mechanism between said plates and one of said followers for forcing said plates into frictional engagement with one another, and an application spring between said toggle mechanism and the other of said followers through which buffing and pulling forces imposed on the gear are transmitted to said toggle mechanism.

9. In a draft gear, in combination, a pair of opposed chambered followers, cooperating friction elements housed within said followers, friction shoes in each follower for engaging said elements, toggle members in each follower, spring means engaging said toggle members for creating a lateral pressure on said shoes and elements upon the compression of said gear, and resilient means for resisting the inward movement of said shoes during compression of the gear.

JAMES R. CARDWELL.
